UNITED STATES PATENT OFFICE.

HENRY D. LENTZ, OF FREMONT, IOWA.

ADJUSTABLE BEARING.

SPECIFICATION forming part of Letters Patent No. 783,874, dated February 28, 1905.

Application filed October 19, 1904. Serial No. 229,193.

To all whom it may concern:-

Be it known that I, HENRY D. LENTZ, a citizen of the United States, residing at Fremont, in the county of Mahaska, State of Iowa, have 5 invented certain new and useful Improvements in Adjustable Bearings; and I do hereby declare the following to be a full, clear, and exact description of the invention, such as will enable others skilled in the art to which it applies 10 to make and use the same.

This invention relates to bearings, and more particularly to shaft-bearings, and has for its object to provide a bearing which may be adjusted in a simple and rapid manner to compensate 15 for wear of the parts.

Other objects and advantages will be apparent from the following description, and it will be understood that variations in the form and proportion shown and described may be made 20 and that any suitable materials may be used without departing from the spirit of the invention.

In the drawings forming a part of this specification, and in which like numerals of reference 25 indicate similar parts in the several views, Figure 1 is a vertical longitudinal section of the bearing. Fig. 2 is a horizontal longitudinal section. Fig. 3 is a transverse section taken on line 3-3 of Fig. 1. Fig. 4 is 30 a side elevation of the complete bearing. Fig. 5 is a horizontal longitudinal section showing a modification in which the wings and recesses are omitted.

Referring now to the drawings, there is 35 shown a supporting-bracket 5, through the head 6 of which there is formed a passage 7, and at one end of this passage there is an inwardly-directed flange 8, which is threaded on its inner face, as shown at 9. Formed at diametrically opposite points in the sides of the 40 passage 7 are wedge-shaped recesses 10, the vertical side walls 11 of which slant outwardly from the walls of the passage 7 at points adjacent to the end of the passage which lies 45 away from the flange 8, the recesses 10 thus lying with their major ends in the direction of the flange and with the walls of these ends extending horizontally. As usual, the head 6 of the supporting-bracket consists of two 50 portions 6' and 6", which are bolted together,

and in the present instance the division between these two portions extends horizontally through the centers of the recesses 10.

Disposed within the passage 7 there is a bushing 12, which is divided vertically into two portions 12' and 12", each of these portions having a wedge-shaped wing 13 extending laterally therefrom and lying in one of the recesses 10. Each of the sections of the bushing of course has a longitudinally-extending arcuate groove 14 in its inner face, these two grooves together forming a passage for the reception of the shaft 15.

Engaged with the threads 9 of the flange 8 is a cylindrical follower 16, having a central 65 passage 17, in which the shaft is engaged, and at its outer end this follower is provided with an angular flange 18, which may be grasped with a wrench, the inner end of the follower resting against the bushing 12, and it will be 70 understood that this follower may be operated to move the bushing longitudinally within the head, the wings 13 at the same time causing the sections of the bushing to move inwardly and closely fit the shaft. Engaged 75 with the follower outwardly of the flange 8 is a lock-nut 19, which may be moved to impinge against the end of the head and against a band 20, mounted thereon to hold the follower against movement.

Loosely engaged with the shaft 15 at the opposite side of the head from the follower is a collar 21, having a set-screw 22 therein, which may be operated to bear against the shaft and to prevent rotation of the collar 85 thereon. This collar may be moved on the shaft to rest against the end of the bushing, and thus prevent end thrust.

In Fig. 5 there is shown a modification in which both the passage 7 and the bushing 12 90 are angular in cross-sections, the passage and bushing being correspondingly tapered longitudinally away from the flange 8, the recesses 10 and wings 13 being thus omitted.

What is claimed is--

1. In a bearing, the combination with a head having a passage therethrough, said passage having tapered portions, of a bushing including two sections slidably disposed in the passage said bushing having tapered portions cor- 100

responding to the tapered portions of the passage, a follower arranged for movement to bear against the bushing and move the latter in the direction of the minor ends of the tapered portions, means for holding the follower at different points of its movement, a shaft revolubly engaged in the bushing, a collar revolubly mounted upon the shaft and arranged for movement to lie against the end of the bushing and means for holding the collar against rotation upon the shaft.

2. In a device of the class described, the combination with a bracket having a head provided with a passage, said passage having tapered portions, said head having an inwardly-directed interiorly-threaded flange at one end of its passage, a bushing including two sections slidably disposed in the passage and hav-

ing tapered portions corresponding to those of the passage, a threaded follower engaged with the threads of the flange and arranged for movement to bear against the bushing and move the latter within the passage and toward the minor ends of the tapered portions thereof to move the sections of the bushing toward each other, and a lock-nut engaged with the threaded follower exteriorly of the head and arranged for operation to impinge against the head to prevent movement of the follower.

In testimony whereof I affix my signature in presence of two witnesses.

HENRY D. LENTZ.
